UNITED STATES PATENT OFFICE.

FRANK L. IRWIN, OF COLUMBUS, OHIO, ASSIGNOR TO THE RALSTON STEEL CAR COMPANY,
OF COLUMBUS, OHIO, A CORPORATION OF OHIO.

CAR-UNDERFRAME CONSTRUCTION.

No. 900,375.

Specification of Letters Patent.

Patented Oct. 6, 1908.

Application filed January 18, 1908. Serial No. 411,517.

To all whom it may concern:

Be it known that I, FRANK L. IRWIN, a citizen of the United States, residing at Columbus, in the county of Franklin and State 5 of Ohio, have invented certain new and useful Improvements in Car-Underframe Construction, of which the following is a specification.

My invention relates to improvements in 10 car underframe construction, and consists especially in the provision of trussing or bracing means provided at the cross bearer and at the bolster of a car underframe; the arrangement of parts and their attachment 15 to each other and to the center sill provide a stronger and more readily built construction than has hitherto been used, as well as providing a lighter underframe. The truss or 20 bracing construction is so formed as to provide a support for the stringers and the side sills, as well as to provide a very strong supporting construction beneath the center sill.

A further object of my improvement is 25 also to cheapen and simplify the construction of a car underframe.

In the accompanying drawings which are hereto attached and hereby made a part of 30 this specification, Figure 1 is a plan view of the car underframe showing my improved construction both at the bolster and the cross bearer; Fig. 2 is a side view of the car underframe shown in Fig. 1; Fig. 3 is a transverse section through the car underframe at the cross bearer, showing one form of my improved bracing construction; Fig. 4 is an end 35 view of the construction shown in Fig. 3; Fig. 5 is a perspective of a modified form of my improved bracing construction.

Reference being had to the drawings in 40 which the same numeral indicates the same part throughout, the center sill construction of the car underframe is shown at 1, a bolster at 2, a cross bearer at 3, side sills at 4 and 5, an end sill at 6, and stringers at 7, 8, 9, and 45 10; a greater number of stringers may be provided if found advisable. The center sill, as shown is formed of the side channels 11 and 12, the top cover plate 13, and the cross bearers and bolsters are shown securely connected with the side channels of the center sill by the angle plates 14 and 15, the latter being secured to the center sill by the rivets 17, which are provided in sufficient number 50 to perform the function effectively. At the 55 cross bearer I also provide a bearing member

or plate 18 for the stringers, and the latter are secured therethrough by the pins or rivets or bolts 19; the bearing surface being widened by the provision of the bearing member 18, the tendency of the stringer to abrade or shear 60 is materially lessened. A bearing member 20 at the bolster is also provided, which is secured to the bolster by means of the rivets 21, and the stringers are firmly pivoted upon the bolster bearing member 20 by means of the 65 rivets or bolts 22, the purpose accomplished here being also the provision of a wider bearing surface for the stringer to decrease the tendency to shear or abrade, under the severe 70 conditions of usage to which the car is subjected. It is noted that the bearing members 18 and 20 have their inner ends abutting against the side channel of the center sill at their inner ends 23, and at their outer ends are extended as required by the number of 75 stringers provided, in the drawings the outer ends being shown at 24 and 25. The side channels of the center sill are supported internally by the plate 26 interposed between the same and flanged at its lateral edges and 80 secured to the side channels by means of the rivets 27, whereby a strong bracing construction is formed.

The cross bearer 2 at its ends is slit downwardly to form shelves 28 and 29, upon which 85 the side sills 4 and 5 are positioned; an end view of the cross bearer is shown in Fig. 4; it is understood that the ends of the bolster are similarly formed for the same purpose. Reference is hereby made to my pending application No. 378,375 for a similar construction 90 at the end of the bolster and cross bearer, and I need not describe the same further herein.

To brace or support the underframe construction at bolster and cross bearer, I provide the angle 30, secured at one end to the depending plate 31 by the rivets 32, which plate is at its upper edge secured to the cross bearer or bolster by means of the rivets 33; the opposite end of the angle 30 is secured in 100 a similar manner. The angle 30 at its middle portion 34 lies beneath the center sill, and is inclined upwardly at its ends as shown; the second angle 35 is positioned adjacent to the angle 30, and is similarly shaped throughout, 105 and the plate 31 at its lower side passes between the angles 30 and 35, and the rivets 32 consequently pass through the two angles and the interposed plate member. Beneath the center sill is positioned a T-bar 36, with the 110

flange portion positioned beneath the lower flanges on the center sill channels, and secured thereto by means of the rivets 37 and 38; the web of the T-bar 36 is received by the 5 angles 30 and 35 between the same as appears at 39, and rivets 40 are then inserted through the angles and the interposed T-bar web, whereby the construction is very securely fastened together. The angles 30 10 and 35 may be positioned with the flange portion upwardly (not shown), in which case the T-bar 36 may be dispensed with, inasmuch as the flange portions of the angles are positioned beneath the lowermost flanges on 15 the channels of the center sill and sustain the same and also provide a flange for the insertion of rivets thereto to secure the said angles to the center sill. I also provide the reinforcing plate 41 positioned beneath the angles 20 as shown in Fig. 3, and bent to conform to their shape, and riveted thereto at 42. The reinforcing plate 41 may also be provided on the opposite side of the angles 30 and 35, to form a counterpart for the plate 25 31, or it is apparent that a single plate may be provided to extend beneath the angles below the center and along the inclined portions of said angles to any point desired.

In Fig. 5, I have shown a modified form of 30 construction of my improvement, in which the channel 43 is inserted through the side channels of the center sill, and extends from one side sill to the other completely across the car underframe, and provides a firm 35 foundation for the stringers. At its ends said channel 43 is securely riveted at 44 to a flanged member 45, having the shelf 46 provided thereon for seating the side sill 4. Essentially this flange member 45 is formed of a 40 short T-bar bent appropriately to form the said seat 46. To the curved web 47 of the said flange member 45 I secure by means of the rivets 48 the angles 49 and 50, and incline the same downwardly to the center sill construction, where the said angles assume a 45 horizontal position beneath the center sill construction at 51, the opposite end of the angle being upwardly inclined in a manner similar to that shown at 49, and similarly 50 secured to a flange member positioned at the opposite end of the channel 43. As shown in Fig. 5, the angle 49 ends beneath the center sill, and a similar angle 52 is provided for the opposite side of the bracing construction; 55 however, the angle may be formed continuous instead of providing the two sections 49 and 52. In a similar manner the angle shown at 50 may be provided in two sections or may consist of a single member. The 60 angles may be positioned with a lateral flange below as shown in Fig. 5, or may be reversed so that the wide flange portion will be above and beneath the lowermost flanges of the channels forming the center sill, to which 65 they may then be secured by means of rivets

in a well known manner, which is not disclosed in the drawings and which need not be further described. In the construction shown in Fig. 5, the angles are positioned with the wide flange portion below, and I 70 therefore provide for positioning beneath and in engagement with the lower flanges on the center sill channels the T-bar 36 which has been sufficiently described above; it being understood that the T-bar shown in Fig. 75 3 between the angles and the center sill and designated at 53, is practically identical with the one shown at 36.

It is further pointed out that the flange member 45 provides a seat for the side sill 4, so 80 a point of attachment for one end of the channel 43, and means to which the ends of the angles 49 and 50 may be secured, the curved web 47 being positioned between the ends of said angles; whereas in the construction 85 shown in Fig. 3, the plate member 31 to which the ends of the angles 30 are secured have no connection with the seat provided for the side sill.

The truss or bracing construction herein 90 described and provided at the cross bearer and at the bolster of a car under-frame, is simple, very securely put together, and binds all the supporting parts firmly to the center sill.

What I claim is:

1. In a car underframe a center sill, a flange member positioned beneath said center sill transversely and secured thereto, transverse angles beneath said center sill between which angles a flange of said flange member is adapted to be positioned and to which flange said angles are firmly secured, a transverse member mounted upon said center sill and means at the ends of said transverse member for supporting the ends of said angles.

2. In a car underframe a center sill formed of side channels, a T-bar positioned beneath said center sill and secured to said channels, parallel supporting angles embracing the depending flange on said T-bar and being secured thereto, a transverse member mounted on said center sill, supporting members depending from the ends of said transverse member and positioned between the ends of said supporting angles and secured thereto.

3. In a car underframe, a center sill formed of side channels secured together, a transverse channel mounted on said center sill and forming a support for the underframe stringers, a flange member secured at the end of said transverse member and shaped to form the seat for the side sill, a T-bar positioned transversely beneath said center sill and secured to the channels thereof, supporting angles embracing said T-bar and secured thereto, said angles at their ends being secured to said flange member, whereby a truss construction for said car underframe is formed.

4. In a car underframe, a center sill, a flanged member positioned transversely on the under side thereof, transverse truss members receiving said flanged member between themselves and being secured thereto, an upper transverse member borne upon said center sill, said truss members and said upper transverse member being connected together at their outer extremities.
- 5 10 5. In a car underframe, a center sill, a flanged member positioned transversely on the under side thereof, transverse truss members secured thereto, an upper transverse member borne upon said center sill, a seat-forming member mounted upon the end of said upper transverse member and connected
- 15

with the adjacent ends of said truss members.

6. In a car underframe, a center sill, a flanged member positioned transversely on the under side thereof, transverse truss members secured thereto, an upper transverse member borne upon said center sill, and a seat-forming member mounted upon the contiguous ends of said upper transverse member and said truss members.

In testimony whereof I affix my signature in the presence of two witnesses.

FRANK L. IRWIN.
